United States Patent Office

Des. 229,586
Patented Dec. 11, 1973

229,586

HOLDER FOR A TOKEN COIN

Donald J. Frost, 2506 W. Crescent,
Racine, Wis. 53403

Filed June 7, 1971, Ser. No. 150,886

Term of patent 14 years

Int. Cl. D3—02

U.S. Cl. D87—3 B

FIG. 1

FIG. 2

FIG. 1 is a front elevational view of a holder for a token coin, showing my new design; and

FIG. 2 is a side elevational view thereof.

I claim:

The ornamental design for a holder for a token coin, as shown.
